(57) **CLAIM**

The ornamental design for a power supply unit, as shown and described.

DESCRIPTION

FIG. 1 is a perspective view of a power supply unit.

FIG. 2 is a front elevation view thereof. The rear elevation view is identical to the front elevation view.

FIG. 3 is a right side elevation view thereof. The left side elevation view is identical to the right side elevation view.

FIG. 4 is a top plan view thereof.

FIG. 5 is a bottom plan view thereof.

FIG. 6 is an enlarged cross-sectional view taken along the line 6-6 in FIG. 4.

FIG. 7 is a perspective view thereof, shown in an environment of use; and,

FIG. 8 is a perspective view thereof, shown in a second environment of use.

The broken lines shown in the drawings illustrate portions of the power supply unit that form no part of the claimed design.
